UNITED STATES PATENT OFFICE.

NORMAN P. COLLIS, OF DUBUQUE, IOWA.

SANDPAPERING-MACHINE.

SPECIFICATION forming part of Letters Patent No. 759,865, dated May 17, 1904.

Application filed April 27, 1903. Serial No. 154,440. (No model.)

To all whom it may concern:

Be it known that I, NORMAN P. COLLIS, a citizen of the United States, residing in the city and county of Dubuque and State of Iowa, have invented certain new and useful Improvements in Sandpapering-Machines; and I do hereby declare the following to be a full, clear, and exact description of the invention, which will enable others skilled in the art to which it applies to make and use the same.

My invention has relation to sandpapering-machines, more especially such as may be used in the manufacture of patterns and that class of work; and the object is to provide a sandpapering-machine which can be adapted to nearly every surface for finishing or polishing wood or metal patterns.

The leading features of the invention consist in a disk upon which is placed sandpaper or other roughened surfaces and a table adapted to be adjusted at any angle with reference to the disk and to hold the work in operative relation to the disk at any such adjustment.

It also consists in the means attached to the table for the bringing into position and holding circular, cylindrical, cone, and conic shaped bodies and the like, whereby they may be operated upon by the sandpapering-disk, and in providing a gage for the purpose of assisting in operating upon square or angular work.

It further consists in a drum or cylinder covered with sandpaper and in the appliances for holding work whereby the drum may be conveniently adapted to operate upon the centers and the insides of cylindrical and other concave surfaces.

The nature and operation of my improvements will be readily understood by all conversant with such matters after the following explanation, when taken and read in connection with the drawings accompanying the same.

Figure 1 is a perspective view of my machine. Fig. 2 is a vertical section. Fig. 3 is an end view of the drum end with the attachments to the frame. Fig. 4 is a horizontal section through the line A A of Fig. 1. Fig. 5 is a front elevation of the disk and attachments. Fig. 6 is a plan view of the table with

slide and gage. Fig. 7 is a vertical section of the table and of the clamping device for the slide in the table with part cut away. Fig. 8 is a perspective view of the gage for the drum and the device for setting the gage at an angle to the drum. Fig. 9 is a detail of the supporting-plate of the angle-bracket. Fig. 10 is a perspective view in detail of one of the operating-levers. Fig. 11 is a perspective view of the machine with table turned down. Fig. 12 is a detail of part of the appliances for operating the gage for the drum.

Like figures of reference denote corresponding parts in each of the drawings.

Referring to the drawings, 2 designates the frame, which is preferably of cylindrical shape and spreading at the base, through which it may be secured to the floor. The upper end terminates in two arms 3 and 4, which provide the bearings for a shaft 5 and also the usual lubricating-boxes 1 for the shaft. Between the arms on the shaft is secured a driving-pulley 6, which is belted to the power. Upon one end of the shaft outside of the arm 3 is fastened a disk 8, and upon the same shaft outside of the arm 4 is secured a drum 9. The disk 8 and the drum 9 are supplied with sandpaper, emery, or otherwise roughened. Against the opposite sides of the frame are secured the lugs or plates 10 and 12. To the plate 10 is attached the appliances for operating a gage 14 and to the plate 12 means for operating a table 15.

For the purpose of operating the table 15 there is attached to the plate 12 two parallel arms 20, which project out at nearly right angles to the frame, and on their outer ends is secured a shaft 21, around which is secured a clamp 22, provided with arms 25. In the top of the arms 25 is pinned a round shaft 26, around which is secured a clamp 28, having lugs or ears 27, and to the top of the clamp is fastened a table 15 by the screws 29. Through the outer ends of the clamp is inserted a screw 30 to hold the clamp by friction on the shaft 21. For the purpose of operating this screw, whereby the table may be turned away from the disk, in the screw-head 32 is pivoted a swivel-handle or operating-lever 42, adapted

to be raised and lowered vertically or turned to operate the screw 30. By this mode of attaching the table it may be turned entirely away from the disk by simply loosening the 5 screw by the lever 42 and turning the table down, as shown in Fig. 11.

Whenever it is desired to adjust the table at an angle to the disk or sanded surface 8, there is inserted through the ears 27 of the clamp 10 a screw 40, in the head of which is pivoted a lever or swivel-handle 33 and operated in the same manner as the screw 30 is operated by the lever 42. In this manner by loosening the screw 40 by the lever 33 the table 15 may be adjusted at an angle, and then by the lever 33 the screw 40 is drawn up and holds the table at such an adjusted angle.

For the purpose of additionally sustaining the table at right angles to the disk 8 there is 20 hinged to the end of the shaft 21 a brace 35, which may be brought up and engage the under edge 36 of the table. When it is desired to use the table at an angle to the disk, as shown by the dotted lines in Fig. 2, it will 25 be seen that if the brace 35 is removed and the clamp 28 loosened and the outer edge of the table pressed down at that angle the edge 45 next to the disk would be thrown considerably away from the disk and too far for successfully operating the work, and to avoid this and to have the table assume the position as shown in dotted lines, with the edge 45 in 30 its proper relation to the disk, there is attached upon the clamp 22 a lug 48. (Shown 35 in Figs. 2 and 4.) Between the two arms 20 is secured a bracket 50 by a screw 51. Upon the bracket is fastened a slide 52, on which the lug 48 rests or engages the top of the slide when the table is at right angles to the disk, 40 as shown in full lines in Fig. 2; but when the table is tipped to an angle this slide 52 is withdrawn, and the lug 48 will move down past the slide 52 and will allow the table to be tipped and the edge of the table assume 45 the position shown in dotted lines, with the edge 45 in proper relation to the disk for operating upon the work effectively.

When it is desired to operate upon the outside of cylinders, cones, or concave surfaces, 50 there is set in a groove in the face of the table 15 a slide 55, (see Figs. 6 and 7,) in which a pin 56 is set, preferably near one end. This slide is held by a thumb-screw 58, which engages a tapering bolt 60, passing through the 55 table. Between this bolt and the slide 55 is a slide 61. The manner of use of this pin is as follows: The work is pressed down on this pin 56, which acts as a pivot for the work, and the thumb-screw 58 is turned, drawing 60 down the bolt 60 and crowding the slide 61 against the slide 55, and thus holding the slide 55 firmly in the groove.

Upon the table is pivoted a gage 62 by the pivot-pin 64, adapted to be set at any angle 65 by the set-screw 65 in the slot 66.

For the purpose of operating upon the drum 9, whereby the inside of cylinders, concave surfaces, and the like are finished, there is provided a gage 14, which is preferably of the shape shown in Figs. 3 and 8: A square 70 bar 68 is secured in the gage at right angles to it, and around the bar is a clamp 70, provided with outwardly - projecting lugs 71, through which passes a screw 72. This screw is operated by a lever 75, pivoted in the head 75 of the screw in a similar manner to the screw 30 and the lever 42. This permits the gage to be moved along the drum and set an any position relative to the drum.

For the purpose of adjusting the gage 14 to 80 an angle to the drum there is adjustably fastened to the plate 10 another plate, 78, provided with a slot 80 and held adjustably by a screw 81. The plate is provided with two arms 82, which project upwardly, and on their 85 top is cast a plate 84. On the top of the plate 84 is a right-angle plate 86, in which is a slot 88 and a bolt 89, provided with a nut passing through the slot 88 and also through a plate 90, subsequently to be described, and 90 holds adjustably the gage 14.

Beneath the plate 84 is another plate, 90, which is slotted at 92, and at one end are lugs 93, adapted to engage the end of the plate 84. In the slot 92 is pivoted a cam 95, having a 95 handle 96 for operating the same. The plate 86 is preferably cast integral with the clamp 70.

In operating the gage 14 it is set as shown in Figs. 1, 3, and 8, with the inner edge nearly to the surface of the drum, and the lever 75 100 is turned, drawing up the screw 72, which closes the clamp 70 on the bar or shaft 68, and the gage will then be rigidly held where it is set.

When it is desired to change the position 105 of the gage along the drum, the screw 72 is released by the lever 75, and this releases the clamp upon the shaft 68, and the shaft, with the gage attached, is slid along in the clamp 70 to the point desired or may be withdrawn 110 entirely from the clamp.

When it is desired to vary the angle of the gage to the drum, the bolt 89 is released by lifting the handle 96 and turning the cam 95. 115 This permits the plate 86 to be moved longitudinally or turned at any angle on the bolt 89, and in this manner the gage is also turned to any angle to the drum.

It is manifest that since the gage 14 may be set at any position along the drum and at 120 right angles to it cylinders having their ends at right angles to the plane of their surfaces can be readily operated upon in their inner sides by inserting the drum within the cylinder and pressing the end of the cylinder against 125 the gage. It will also be seen that since the gage may be set at any angle to the drum cylinders or concave surfaces which have ends cut at any angle other than a right angle to the plane of its surface may be readily oper- 130

ated upon by simply turning the gage 14 to correspond to the angle of the ends of the concave surfaces and operating as before.

With this construction and operation of the 5 sanded surfaces, together with the manipulation of the table and gages, there will rarely be found a surface which cannot be operated upon, and not necessarily by an expert.

Having now described my invention, what I 10 claim is—

1. In a sandpapering-machine, a frame, a shaft, a cylindrical sanded surface adapted to rotate with the shaft, a gage substantially as described and shown, and means for setting 15 and holding the gage at any position along the sanded surface or at an angle to it.

2. In a sandpapering-machine, a frame, a shaft journaled in the frame, a sanded surface adapted to be rotated by the said shaft, a gage, 20 means for setting the gage in operative relation along the sanded surface consisting of a shaft attached to the gage a clamp on the shaft and a lever for operating the clamp.

3. In a sandpapering-machine, a frame, a 25 shaft journaled in the frame, a cylindrical sanded surface adapted to be rotated with the shaft, a gage 14, curved at its inner edge to

conform somewhat to the surface of the curve of the cylinder, and means for setting the gage at an angle to the sanded surface consisting 30 of a shaft to which the gage is attached, a clamp on the shaft, a plate attached to the frame and provided with a slot, and means engaging said slot to adjustably secure the plate upon the frame and the gage at an angle to the sanded 35 surface.

4. In a sandpapering-machine, a frame, a shaft journaled in the frame, a cylindrical sanded surface adapted to rotate with the shaft, and a gage 14 adapted to be set at any position along the sanded surface and at an angle 40 to it consisting of arms attached to the frame, a plate 84, a plate 86 adjustably attached to the arms, a clamp attached to the plate 86, a shaft engaging said clamp to which the gage is 45 attached and a lever for operating said clamp.

In testimony whereof I have signed my name to this specification in the presence of two subscribing witnesses.

NORMAN P. COLLIS.
